DESIGN FOR A DUSTING POWDER CONTAINER

Basil Saban, New York, N. Y., assignor to Prince Matchabelli Perfumery, Inc., New York, N. Y., a corporation of New York

Application May 7, 1936, Serial No. 62,524

Term of patent 14 years

To whom it may concern:

Be it known that I, Basil Saban, a citizen of Russia, residing at New York, county and State of New York, have invented a new, original, and ornamental Design for a Dusting Powder Container, of which the following is a specification, reference being had to the accompanying drawing, forming a part thereof.

In the drawing:—

Fig. 1 is a top plan view of a dusting powder container showing my new design.

Fig. 2 is a side elevation taken from the line 2—2 of Fig. 1.

Fig. 3 is a side elevation taken from the line 3—3 of Fig. 1.

I claim:

The ornamental design for a dusting powder container substantially as shown.

BASIL SABAN.
